UNITED STATES PATENT OFFICE

2,431,971

METHOD AND MEANS FOR BEVELING AND
SHAPING SHIP FRAMEWORK

Benjamin F. Thompson, Jacksonville, Fla., assignor of one-half to Arthur Lutzen, Jacksonville, Fla.

Application June 27, 1944, Serial No. 542,367

10 Claims. (Cl. 153—28)

1

This invention relates to a treating device for flanged frame members. The primary object of the invention is to provide a mechanism and supplemental method of shaping, and in instances beveling, the flange of a preformed beam, girder or the like having a web and offset flange or flanges customarily present, for example, in beams of U-shape cross-section, in the use of which, dependent upon the purpose for which it is intended, it is necessary or desirable that the flange portion be variously disposed to the web or base portion in order to conform to the shape or contour of the member, as a wall, supported or braced by the beam.

Specifically, the invention finds an important field of usefulness, and performance beneficial in the making of framework structures for the hulls of boats, and will be equally serviceable in other connections, wherein the hull or structure to be supported or braced has a change in contour, as the longitudinal tapering or contouring of the hull fore and aft, as well as the curving of the wall in a general vertical direction from the keel into the sides of the boat.

In meeting the conditions related, and effecting a close fit of the framework with the superposed hull structure, the adjoining flange of the beams of the framework must be disposed at varying angular relationships to the web of the beam and heretofore a practice has been to manipulate a finished beam to change the angularity of the flange relative to the web to first bodily bend the beam to obtain the general contour thereof longitudinally and then by the employment of hammers and flatters to change the angularity of the flange, and bevel the flange, when desired, in a cold state of the metal of the beam. This has proven to be an undesirable method because of the time consumed, the added difficulty of bending the flange to give it the desired angular position after the general curving of the beam as a whole, because of the delays and cooling of the beam being treated and because the hammering is a relatively crude and tedious performance.

Having in mind, as an example, that it has been found in practice in shipbuilding that the angularity of the flange of the beam will vary possibly as much as 20° in a piece of channel or angle iron of approximately 30 foot length, the desirability of a mechanism to accomplish the result in connection with the beam immediately as it comes from a preheater so that the completed work may be accomplished with minimum manual help or labor, in approximately 8 to 10 seconds for a 30 foot beam or frame member, the

2

accomplishments of the present invention are emphasized and appreciated.

The preferred embodiment of the invention is illustrated in the accompanying drawings and will be clear when read in connection with the specific description hereinafter contained.

Such embodiment embraces the utilization of a suitable base member over which the flange beam may be passed as delivered from a preheater, and 10 means operatively associated with said base comprising a pair of deflecting rollers, through which the flange to be treated may pass, adjusting means for the rollers to approximately axially dispose the same whereby to bend or treat the flange as it 15 moves across said base combined with a manually adjustable presser roll for holding the opposite flange or edge portion of the beam towards the base as determined by varying degrees of pressure controlled by the operator.

20 The combination preferably has provision in connection with the bending rolls for also effecting a tapering of the flange transversely thereof when desired. The arrangement of the pair of bending or beveling rolls and the pressure or holding roll 25 is such that as the manual pressure on the latter varies to hold the web of the beam flat against the base or permit the same to rise, as in tilting the edge of the beam remote from the shaping rolls upwardly from the base under the influence 30 of the shaping rolls, the flange of the beam being treated will consequently vary, as controlled, in its angular relation to the web of the beam throughout the length of the beam.

Referring to the drawings—

35 Figure 1 is a perspective view of the machine.
Figure 2 is a top plan view thereof.
Figure 3 is a longitudinal sectional view taken on the line 3—3 of Fig. 2.

Figure 4 is an end view of the machine (right 40 end of Fig. 1).

Figure 5 is a vertical section through the shaping and beveling rolls, and associated parts mounting the same with a U-shaped beam in operating position.

45 Figure 6 is a diagonal elevation illustrating different positions assumed by a U-beam under treatment.

Referring more particularly to the drawings in which the same reference numerals will be identical parts throughout said drawings 10 represents a metal base plate of substantial thickness and width to give the same the strength and rigidity required, the same as is true of the other parts of the apparatus—said plate being of substantial width to permit proper passage and sup-

port of a beam to be treated thereover, and also elongated sufficiently to accommodate the shaping or beveling mechanism. This plate 10 is intended to be supported on the floor surface in juxtaposition to and parallel with the front or discharge end of a heating oven or furnace from which the beam is immediately withdrawn and passed over the base plate transversely of the latter. The plate is firmly anchored to the floor, customarily of perforated iron plates, by appropriate fastening means, such as spikes 11, embedded in the floor and engaging the edges of the plate, the latter having upstanding rods or standards 12 looped at their upper ends 13 and extended from the opposite ends of the plate for convenient grasping in carrying and positioning the machine in proper position when disposing the same for anchoring or removal with reference to the floor.

The treating mechanism, mounted on and carried by the base plate, comprises two operatively related sections, one arranged near one end of the supporting bed or plate 10 and the other near the opposite end of said plate and suitably spaced apart to provide for the passage therebetween of the beam under treatment, one of these sections denoted 14 and the other 15. The section 14 is a means for creating a desirable degree of depression or pressure on the near edge or flange of the beam 16 being treated to determine the degree of hold of said beam in flat condition against the bed plate 10, or the degree of lateral tilt of the web of the beam upwardly out of parallel relationship of the web with the surface of the bed plate under the influence of operating rolls of the section 15, which is the shaping or beveling section.

The shaping or beveling section 15 comprises a carrier head or block 17 of rectangular cross section to provide vertical parallel sides 18, adapted to work between corresponding surfaces 19, of supporting and guiding brackets 20 and 21 integral with the base plate 10, and suitably spaced apart to accommodate the width of the carrier head or block 17 which is pivoted to swing in an arc within a vertical plane upon a horizontal shaft 22 bridging the space between the uprights 20 and 21 and engaging therewith at its ends, with the intermediate portion thereof passing through the block 17 and thereby affording the instrumentality whereby said block may turn for the arcuate adjustment referred to.

Mounted free for rotatable support by the block 17 are a pair of cooperating flange-bending or beveling rollers 23 and 24, mounted on vertical rotatable shafts 25 and 26, passing through the carrier block 17 and having suitable bushings or washers 27 and 28 (brass or the like) at the top of the block 17 and also at the bottom thereof between the bottom surface and the upper surface of the rolls 23 and 24. Suitable nuts 29 and 30 are engaged with the shafts 25 and 26 respectively to hold the shaft 25 in position against dropping from the block 17, pins 31 and 32 passing through the appropriate apertures transversely of the shafts 25 and 26 and projecting to overlie the nuts and fit in recesses 33 and 34 of them, to interlock the shaft nut and roller together for rotative movement within and against the bushings. The idea of providing the series of apertures as 35, referred to, is to enable shafts and rollers of different length or size to be mounted in the block alternatively as working conditions demand. When rocking the block 17 and rollers carried thereby to its various predetermined adjusted positions, fastening means for fixing the

same are utilized, the same being in the nature of binding screws 36 having engagement with threaded portions 37 in the uprights 19 and 20, the binding screws 36 passing through complementary threaded openings in said uprights and at their ends impinging upon the side faces 18 of the block to thereby bind the block and parts carried thereby against movement around the axis of the said block or laterally of said axis. 10 At times, incident to extraordinary heavy work, a pair of these binding screws 36 may be used at each side, although usually one only will be sufficient. The bed or base plate 10 has an elongated slot 38 therethrough to accommodate the lower ends of the rolls 23 and 24 when in their lowermost or inoperative position, or the lower end portion of the roll 23 when the feeding of the roll 24 at the inner side of the flange of the beam to bend the same is not required to be sufficiently high for the complementary or backing roll 23 to escape said slot.

From so much of the description already given, it will be understood that a heated flange beam introduced with one edge of the beam between the rolls 23 and 24, and gripped at the protruding end of the flange, as by gripping tongs or other instrument, may be drawn through the rolls 23 and 24, and dependent upon the angularity thereof, with reference to the web of the beam and the position of the web with reference to the surface of the base plate 10, the angle of the flange may be reshaped or the flange deflected from its original preformed condition, as may be desired. Assuming the web to occupy a perfectly flat or parallel position relative to the bed or base plate 10 or permitted to rise under the bending force of the rollers 23 and 24, a regulated pressure is applied to the other or remote edge of the web to firmly hold the same in a position to determine the instant degree of angularity of the flange of the beam being treated relative to the web of the beam. This is accomplished, as stated, through the instrumentality of the section 14 of the machine, which comprises primarily a holding roller 39 of substantial length adapted to bear upon that flange or edge of the beam not under treatment by the section 15. This roll is rotatable on a generally horizontal axis, being sleeved upon and rotatable with reference to an axle 40 on which latter the roller 39 is endwise adjustable through the medium of apertures 41 transversely of the shaft, and pins 42, engaging therewith at the opposite ends of the roller 39. This roller is provided, if desired, with bushings or washers 42' and grooved nut members 42'', for the reception of the pins after the mountings of the engagements of the rollers 23 and 24, hereinbefore described. The axle 40 is extended at its inner end to constitute one end 43 of a toggle lever, the operating end of which is shown at 44. The toggle lever is arranged to swing upwardly and downwardly between uprights 45 and 46, generally in line with the uprights 20 and 21 of the forming section 15 of the machine, and the cooperating members of the lever are joined together through the medium of a pivotal connection 47, the respective members 43 and 44 being in turn mounted and supported by the uprights 45 and 46, through the medium of couplings 47' and 48 of a length to bear against the inner faces 49 and 50 of the uprights 45 and 46, and each having a longitudinal passageway 51, 52 longitudinally therethrough for the reception of the lever members 43 and 44. The coupling members 47' and 48 also have

transverse passages 53 and 54 therethrough in line with interiorly threaded portions 55 and 56, in the uprights 45 and 46. Stub pintles 57 are threaded into the complementary threaded portions 55, of the uprights 45 and 46, and have smooth inner end portions 58 to constitute pivots engaging the transverse passage 53, of the coupling 48, but of a length not to bind the lever portion 44 whereby the latter may slip longitudinally of the coupling 48 to allow for the shortening and lengthening of the toggle in its up-and-down movements. The other coupling member 47' is also provided with a pair of like stub pintles 59 to afford similar pivot bearings for the lever member 43, but in this instance the coupling 47' is held to the lever member 43 by a binding pin or screw 60 fixing the coupling to the lever member 43. While the lever member 44 may adjustably slide through its coupling, the lever member 43 and its coupling are held together against relative movement.

The pairs of uprights 20, 21 and 45, 46 may be reinforced, as desired, or found expedient, a convenient and efficient means being angular braces 61 and 62 integral with the uprights and bed plate 10.

Inclined planes 63 may be formed with or adjoin the bed plate 10 to facilitate the riding of a beam to be treated up onto the surface of the bed plate thereby preventing the catching of the end of the beam on the edge of the plate as the beam is threaded into the machine.

The U, L, I or other beam of flange cross-section, being drawn, preferably at a heat to facilitate bending, between the rolls 23 and 24, the latter having been first adjusted in the predetermined axial inclination with reference to the base, and the web of the beam being held against the base, the rolls 23 and 24 will bend the flange of the beam relative to the web thereof to create the desired angular relationship. All that is necessary is to manually press or relatively decrease pressure on the lever 44 which, on the one hand hold the web of the beam flat against the bed plate or on the other hand lessen such hold and permit the outer edge of the beam to rise under the force of the bending operation of the rolls 23 and 24 to the degree or extent desired in decreasing or increasing the angle between the web and the flange, as the flange beam passes along through the shaping or beveling rolls. To bevel or taper the flange of the beam throughout the width thereof, that is, from the web of the beam to the free edge of the flange, the roll 24 may be increased in diameter in an upward direction so that the space between the rolls 23 and 24 is widest at the lower ends of the roll and tapers up to a relatively fine edge as compared to the juncture of the flange with the web of the beam and this tapering or beveling of the flange may be accomplished simultaneously with the varying angular positioning of the flange relative to the web of the beam as the requirements for the use of the beam dictate, through the travel of the beam through the machine. The apparatus herein set forth is, as first brought out in this specification, one of great rapidity in action while clearly efficient in result.

It is believed that this machine, in addition to the considerations of details pointed out herein, is fundamentally the first wherein deflecting or bending rolls have been suggested in connection with an opposing lever-actuated presser roller, to engage that end of a flange or portion of a beam not being bent, whereby, dependent upon

the force applied to the lever, said roller may hold the beam flat on the base or permit the same to tilt upwardly to various extents, as influenced by the action of the bending rolls so that the angularity or degree of bend of the flange being treated may be in varying degrees to meet the varying conditions of service desired.

Of course, any convenient method of lubricating, and cooling the forming rolls may be resorted to, but for purpose of illustration I have shown the head 17 with suitable nipples or admission ports 64 for the accommodation of grease guns or the like, the interior of the block 17 being hollow and in communication with said ports and adapted to receive lubricant to surround the shafts 25 and 26 of the rolls 23 and 24 for the purpose stated.

It will also be appreciated that bodily bending or curving of the beam may follow immediately upon the work of my machine thereon in the angular forming or positioning or beveling of the flange. While still in the heated state, and before it has a chance to objectionably cool, the beam under treatment may pass straight through the machine and remain bodily straight or upon passage from the shaping, deflecting or beveling rolls, by manipulation or lateral bending attain a general curvature of the beam wanted.

Finally, in the working of my machine and method an important factor in the operation is that through the medium of the holding or presser lever on the outer edge of the beam co-operating with the deflecting or beveling rolls, in the combination hereinabove outlined, every change in the degree of bend or deflection of the flange of the beam being treated may be accomplished as the beam feeds through the machine without necessity of stopping the operation.

I claim:

- 40 1. In a machine of the character described, a support for a flanged beam to be treated, said support being formed and arranged to receive the web of the beam thereon to pass therealong longitudinally of the beam with its flange projected upwardly therefrom, flange treating mechanism mounted adjacent to said support adapted to angularly change the flange relative to the web of the beam as it passes through said mechanism, and a free manually adjustable pressure device operatively related to and aligned with the flange treating device in a plane at right angles to the longitudinal axis of the beam to hold under variable manual pressure the web of the beam at a point directly opposite to the flange treating mechanism against bodily movement under the influence of the flange deflecting mechanism whereby to correspondingly vary the degree of deflection of the flange under treatment.
- 45 2. In a machine of the character described, a support for a flanged beam to be treated, said support being formed and arranged to receive the web of the beam thereon to pass therealong longitudinally of the beam with its flange projected upwardly therefrom, flange roll treating mechanism mounted adjacent to said support adapted to angularly change the flange relative to the web of the beam as it passes through said mechanism, and a free manually adjustable roll pressure device operatively related to and aligned with the flange treating device in a plane at right angles to the longitudinal axis of the beam to hold under variable manual pressure the web of the beam at a point directly opposite to the flange roll treating mechanism against bodily movement under the influence of the flange de-
- 50

flecting mechanism whereby to correspondingly vary the degree of deflection of the flange under treatment.

3. In a machine of the character described, a supporting base for the web of a flanged beam to be treated, said support being formed and arranged to receive the web of the beam thereon to pass therewith longitudinally of the beam with its flange projected upwardly therefrom, flange treating roll mechanism mounted laterally of said support and above the same, said roll mechanism comprising a pair of parallel cooperating rolls on approximately vertical axes, means for adjusting the rolls to have said axes angularly related to the flange of the beam whereby to deflect said flange in keeping therewith as the beam is passed through the machine, and movable means variably adjustable in a vertical direction in a plane at right angles to the longitudinal axis of the beam to engage that edge of the beam directly opposite to said flange treating roll mechanism with corresponding varying pressure to hold the web of the beam in desired positions with reference to said supporting base.

4. In a machine of the character described, a support for a flanged beam to be treated, flange treating mechanism mounted adjacent to said support, and an adjustable presser device operatively related to the flange treating device and adapted to engage the beam at that edge portion thereof opposite said flange, said adjustable presser device comprising a roller, and a lever for actuating the same including an adjustable toggle connection between the engageable portion of the lever and the roller.

5. In a machine of the character described, a support for a flanged beam to be treated, flange treating mechanism mounted adjacent to said support, and an adjustable presser device operatively related to the flange treating device and adapted to engage the beam at that edge portion thereof opposite said flange, said adjustable presser device comprising a roller, and a lever for actuating the same including an adjustable toggle connection between the engageable portion of the lever and the roller, in combination with uprights on the support between which the said toggle connection is mounted and supported.

6. In a machine of the character described, a support for a flanged beam to be treated, flange treating roll mechanism adjacent to said support, and a presser device operatively related to the flange treating device and adapted to engage the beam at that edge portion thereof opposite to said flange, the treating roll mechanism comprising rolls disposed to permit passage therebetween of the flange under treatment, said rolls having approximately vertical axes, a block for supporting said rolls, a pivotal mounting for said block whereby the engaging surfaces of the rolls may be angularly adjusted to correspondingly deflect the flange being treated, uprights on the base for pivotally supporting said block therebetween, and locking means between one of the uprights and said block for securing the block and rolls in adjusted positions.

7. The method of treating metallic flanged beams or the like to provide a flange on the web of said beam disposed at varying angles to the web throughout various portions of the beam, comprising preheating the beam to render the same more susceptible to flange bending, supporting the beam on the side opposite flange deflecting instrumentalities, passing said beam on its web and longitudinally of said beam with the flange to be treated under engagement with the flange deflecting instrumentalities whereby to elevate the web of the beam under the tilting influence exerted thereon by the said instrumentalities, and holding the edge portion of the beam remote to said flanged edge at a point directly in line with the flange deflecting instrumentalities and under manual pressures throughout the travel of the beam to correspondingly control the various changes in angularity of the flange relative to the web of the beam, the engagement of the flange being treated and the holding of the remote edge portion of the beam being in the same plane transversely of the beam and at right angles to the longitudinal axis thereof.

flange to be treated under engagement with the flange deflecting instrumentalities whereby to elevate the web of the beam under the tilting influence exerted thereon by the said instrumentalities, and holding the edge portion of the beam remote to said flanged edge at a point directly in line with the flange deflecting instrumentalities and under manual pressures throughout the travel of the beam to correspondingly control the various changes in angularity of the flange relative to the web of the beam, the engagement of the flange being treated and the holding of the remote edge portion of the beam being in the same plane transversely of the beam and at right angles to the longitudinal axis thereof.

8. The method of treating metallic flanged beams or the like to provide a flange on the web of said beam disposed at varying angles to the web throughout various portions of the beam comprising supporting the beam on the side opposite flange deflecting instrumentalities, passing said beam on its web and longitudinally of said beam with the flange to be treated under engagement with the flange deflecting instrumentalities whereby to elevate the web of the beam under the tilting influence exerted thereon by the said instrumentalities, and holding the edge portion of the beam remote to said flanged edge at a point directly in line with the deflecting instrumentalities and under manual pressures throughout the travel of the beam to correspondingly control the various changes in angularity of the flange relative to the web of the beam, the engagement of the flange being treated and the holding of the remote edge portion of the beam being in the same plane transversely of the beam and at right angles to the longitudinal axis thereof.

9. The method of treating metallic flanged beams or the like to provide a flange on the web of said beam disposed at varying angles to the web throughout various portions of the beam, comprising preheating the beam to render the same more susceptible to flange bending, supporting the beam on the side opposite flange deflecting instrumentalities, passing said beam on its web and longitudinally of said beam with the flange to be treated under engagement with the flange deflecting instrumentalities whereby to elevate the web of the beam under the tilting influence exerted thereon by the said instrumentalities, holding the edge portion of the beam remote to said flanged edge at a point directly in line with the deflecting instrumentalities and under manual pressures throughout the travel of the beam to correspondingly control the various changes in angularity of the flange relative to the web of the beam, and bodily curving or contouring the beam immediately following the flange treating step before the beam has substantially cooled, the engagement of the flange being treated and the holding of the remote edge portion of the beam being in the same plane transversely of the beam and at right angles to the longitudinal axis thereof.

10. The method of treating metallic flanged beams or the like to provide a flange on the web of said beam disposed at varying angles to the web throughout various portions of the beam comprising supporting the beam on the side opposite flange deflecting instrumentalities, passing said beam on its web and longitudinally of said beam with the flange to be treated under engagement with the flange deflecting instrumentalities whereby to elevate the web of the beam under the tilting influence exerted thereon by the said instrumentalities, and holding the edge portion of

the beam remote to said flanged edge at a point directly in line with the deflecting instrumentalities and under manual pressures throughout the travel of the beam to correspondingly control the various changes in angularity of the flange relative to the web of the beam, the engagement of the flange being treated and the holding of the remote edge portion of the beam being in the same plane transversely of the beam and at right angles to the longitudinal axis thereof.
